UNITED STATES PATENT OFFICE.

GEORGE M. GRAHAM, OF CHICAGO, ILLINOIS, ASSIGNOR, BY MESNE ASSIGNMENTS, TO
SUSPENSION STEEL CONCRETE COMPANY, A CORPORATION OF DELAWARE.

FITTING FOR REINFORCING-FRAMES.

976,869.

Specification of Letters Patent. Patented Nov. 29, 1910.

Application filed April 21, 1909. Serial No. 491,343.

To all whom it may concern:

Be it known that I, GEORGE M. GRAHAM, a citizen of the United States of America, and a resident of Chicago, in the county of 5 Cook and State of Illinois, have invented certain new and useful Improvements in Fittings for Reinforcing-Frames, of which the following is a specification.

This invention relates to the particular 10 form of truss girders or beams for skeleton frames of reinforced concrete structures which forms the subject matter of my prior Letters Patent No. 889,223, dated June 2, 1908, and No. 919,714, dated April 27, 1909, and has for its object to provide a simple 15 and efficient structural formation of the coupling pieces adapting the same for substantial connection to the frame posts and beams so that a minimum thickness of the 20 concrete portion of the wall, floor, etc., is required to inclose said connecting parts, and which construction also affords a simple, 25 convenient and effective abutment connection for the truss wires of the beams, all as will hereinafter more fully appear.

In the accompanying drawings:—Figure 1, is a detail perspective view of a corner portion of a reinforcing frame having the present invention applied. Fig. 2, is a detail 30 sectional plan of the same. Fig. 3, is a detail front elevation of one form of the angular coupling piece adapted for the connection of untrussed beams to each other and to the posts. Fig. 4, is a side elevation of 35 the same. Fig. 5, is a detail front elevation of another form of the coupling piece adapted for connecting trussed beams to each other and to the posts and providing means for the attachment of the ends of the 40 tension members of the truss formations. Fig. 6, is a side elevation of the same.

Similar numerals of reference indicate like parts in the different views.

As represented in the drawings the arrangement of the parts will be substantially the same as in my before mentioned Patent 45 No. 889,223, and will involve the usual round corner post or column 1, and round beams or girders 2 connected together and 50 to said post by coupling pieces constructed as follows:—

3 is a coupling piece above referred to, the respective members of which are in angular relation to each other as shown, and have

their outer faces concave to fit the convexity 55 of a round post or beam as in my aforesaid patented construction.

4 are elongated recesses formed in the opposite or inner faces of the coupling members aforesaid by marginal or border flanges 60 5 and adapted to receive the heads or nuts of the fastening bolts 6, the shanks of which pass through orifices in the bottom webs of said recesses and through the post and beam to rigidly connect the parts together. As so 65 constructed a minimum degree of projection of coupling means is provided and in turn entails a corresponding decrease in the thickness of the concrete wall required to properly inclose the parts. As in my former pat- 70 ent construction, pairs of said coupling pieces, arranged on common upper and lower planes, are used in the connection of the ends of adjacent beams to a post of the frame, and in order that the fastening bolts 6, aforesaid, 75 do not interfere with each other a multiple series of bolt holes are formed in each coupling member, aforesaid, in order that the bolts extending in opposite directions through the parts may be readily arranged 80 in the required staggered or alternated relation as illustrated in Figs. 1 and 2. As so formed the one pattern of coupling piece is capable of use in both instances, and materially aids in the process of erection. 85

Another part of the present invention involves the formation of a bracket as above described with anchor or attaching means for the ends of the multiple wire or rod tension members of the beam truss described in 90 my prior Letters Patent No. 919,714, dated April 27, 1909, and consists in the enlargement of a coupling piece at the point of intersection of its members, and the formation of an open side orifice 7 in said enlargement 95 to form opposed horns 8 around which the rods or wires 9 of the tension member of a beam truss are looped, as shown. The truss for a beam above referred to will preferably comprise a pair of lateral struts or queen 100 posts 10, arranged in spaced relation, and having end bearing against a round beam 2. At their other ends said queen posts carry bearing shoes 11 to receive the wire or rod tension members 9 of the truss, as described 105 in detail in my former Letters Patent of April 27, 1909.

Having thus fully described my said in-

vention what I claim as new and desire to secure by Letters Patent, is:—

1. The combination in a skeleton reinforcing frame for concrete structures, of a round post, a pair of round beams in angular relation and abutting against said post, coupling pieces the members of which are in angular relation, each member having a concaved surface on one side to fit a post or beam, an elongated recess in the other side formed by border flanges on the member and a series of bolt holes in the web of said recess, and a series of fastening bolts passing through said members and entirely through the posts and beams, substantially as set forth.

2. The combination in a skeleton reinforcing frame for concrete structures, of a round post, a pair of round beams in angular relation and abutting against said post, coupling pieces the members of which are in angular relation, each member having a concaved surface on one side to fit a post or beam, an elongated recess in the other side formed by border flanges on the member and a multiple series of bolt holes in the web of said recess,

and a series of fastening bolts passing through said members and entirely through the posts and beams in staggered relation, substantially as set forth.

3. The combination in a skeleton reinforcing frame for concrete structures, of a round post, a pair of round beams in angular relation and abutting against said post, coupling pieces the members of which are in angular relation and provided with an enlargement at their point of intersection, the enlargement having an open side orifice forming opposed horns, a series of fastening bolts passing through said members and entirely through the posts and beams, and a lateral truss consisting of intermediate struts and tension members extending from post to post, over said struts, and looped around the horns aforesaid, substantially as set forth.

Signed at Chicago, Illinois, this 12th day of April 1909.

GEORGE M. GRAHAM.
